No. 805,899.

PATENTED NOV. 28, 1905.

R. B. BOLL.

DUSTLESS FEEDER AND MIXER FOR FLOUR MILLS.

APPLICATION FILED JAN. 28, 1905.

UNITED STATES PATENT OFFICE.

ROBERT B. BOLL, OF MULKEYTOWN, ILLINOIS, ASSIGNOR OF ONE-HALF
TO HERMANN LIEBSTER, OF MULKEYTOWN, ILLINOIS.

DUSTLESS FEEDER AND MIXER FOR FLOUR-MILLS.

No. 805,899.

Specification of Letters Patent.

Patented Nov. 28, 1905.

Application filed January 26, 1905. Serial No. 242,744.

To all whom it may concern:

Be it known that I, ROBERT B. BOLL, a citizen of the United States, and a resident of Mulkeytown, Illinois, have invented certain new 5 and useful Improvements in Dustless Feeders and Mixers for Flour-Mills, of which the following is a specification containing a full, clear, and exact description, reference being had to the accompanying drawings, forming 10 a part hereof.

My invention relates to improvements in dustless feeders and mixers for flour-mills; and it consists of the novel features herein shown, described, and claimed.

15 In the drawings, Figure 1 is a vertical cross-section on the line 1 1 of Fig. 2 and looking in the direction indicated by the arrow. Fig. 2 is a side elevation as seen looking in the direction indicated by the arrow 2 in Fig. 3. 20 Fig. 3 is an end elevation looking in the direction indicated by the arrow 3 in Fig. 2. Fig. 4 is a longitudinal sectional detail on the line 4 4 of Fig. 1. Fig. 5 is an enlarged sectional detail of the screen.

25 Referring to the drawings in detail, the sills 6 and 7 are mounted in parallel position upon the floor 8. Posts 9 and 10 extend upwardly from the sill 6, and similar posts 11 and 12 extend upwardly from the sill 7. The upper ends of the 30 posts 9 and 10 are connected by a cross-piece 13, and the upper ends of the posts 11 and 12 are connected by a cross-piece 14. The brace 15 connects the upper ends of the posts 10 and 12, and a similar brace 16 connects the upper 35 ends of the posts 9 and 11. A brace 17 connects the posts 10 and 12 near their centers, and a similar brace 18 connects the posts 9 and 11 near their centers. A brace 19 connects the posts 9 and 10 at points a short dis-

40 tance below the braces 17 and 18, and a similar brace (not shown) connects the posts 11 and 12. The space between the posts 9 and 10 and the cross-piece 13 and brace 19 is closed by a wall 20, and the same space between the posts 11 and 12 is closed by a wall 21, and a sliding wall 22 closes the space between the posts 9 and 11, and a similar sliding wall 23 closes the space between the posts 10 and 12. Bearings 24 are mounted 45 upon the brace 19 and the opposite brace, and a shaft 25 is mounted in the bearings, there being a driving-wheel 26 upon one end of the shaft. The shaft 25 extends through the walls 20 and 21. A hopper is constructed

around the shaft 25 and comprises the inclined 55 wall 27, the oppositely-inclined wall 28, and the semicircular wall 29, connecting the lower edges of the walls 27 and 28 concentric to the shaft 25, there being a screen-opening 30 in said wall 29. Hubs 31 and 32 are 60 mounted upon the shaft 25 just inside of the walls 20 and 21 and held adjustably in position above said screen. Each beating-arm consists of the center portion 33 parallel with the shaft 25 and the end portions 34 and 35 65 at right angles to the center portion and adjustably mounted in sockets in the hubs 31 and 32.

The screen comprises the foraminous sheet 36, the lower frame member 37, and the upper frame member 38, said frame members being secured together to clamp the edges of the foraminous sheet and said frame members being so shaped that the foraminous sheet is above the upper face of the upper frame member. The screen is concavo-convex and fits in the opening 30 in the wall 29, said screen being removed and replaced through the opening 39. A shutter 40 is slidably mounted below the screen, said shutter being moved by 70 the handle 41 to control the opening 30 and regulate the amount of flour or feed which may pass through the opening. Beater-arms 33 are adjusted to and from the screen by the set-screws 42 in the hubs 31 and 32. A door 85 43 is in position to close the opening 39. A cover 44 closes the flour-box within the walls 20 21 and 22 and 23.

The flour or feed may be emptied into the flour-box by removing the cover 44 or by raising either wall 22 or 23, and said walls provide access to the flour or feed box for any purpose.

The device is used as a feeder and mixer for flours and for feeding and mixing off-grade 95 flour, feeding material from choke-ups, &c. By manipulating the handle 41 the feed is accurately adjusted.

A spout 45 leads downwardly from the opening 30, and spouts 46 and 47 lead from 100 the spout 45, there being a wind-valve 48 pivotally mounted, as usual, between the upper ends of the spouts 46 and 47 and there being a hand-hole 49, normally closed by a slide 50, through which the wind-valve may be operated, so that when the valve is thrown to the right the flour will pass to the left through the spout 46, and when the valve is thrown to the

left the flour will pass to the right through the spout 47.

I claim—

In a dustless feeder and mixer for flour-mills: 5 a shaft rotatably mounted; a hopper having walls curved and concentric to the shaft, and having a discharge-opening; a screen in the discharge-opening; a beater-arm adjustably mounted upon the shaft; a curved shutter for 10 regulating the passage through the screen and

a handle connected to said shutter and extending outwardly therefrom.

In testimony whereof I have signed my name to this specification in presence of two subscribing witnesses.

ROBERT B. BOLL.

Witnesses:

W. C. BASTIN,
I. M. CAMPBELL.
